MAGNETO

Hugo Ruppe, Berlin, Germany; vested in the
Alien Property Custodian

Application November 7, 1939, Serial No. 303,320
In Germany June 21, 1939

3 Claims. (Cl. 171—209)

The invention relates to magnetos for auxiliary engines for vehicles, especially cycles.

The details of the invention and the advantages it furnishes, are set forth in the following description of the accompanying drawing which represent a typical embodiment of the invention.

Figure 1 is a vertical section through the crank case; and Figures 2 and 3 show the ignition-current generator, in horizontal and vertical section, respectively.

In all the figures, corresponding parts are indicated by the same reference characters.

One of the fly wheels 10, 11 of the two crank-shafts of a cycle engine is constructed of non-magnetic material (such as brass, or nickel-steel), and a magnet 118 of hardened steel with high coercive properties, is inserted in the member 10, whilst two soft-iron pole shoes 119 are integrally cast with the crankcase. Between said pole shoes, the wall of the case is slotted, to prevent electric braking fluxes from being induced in the wall of the crank case during the passage of lines of magnetic force through the pole shoes 119. The slot 120 is filled, gas-tight, with insulating material, to prevent leakage in the crankcase, which serves as a suction chamber. Outside the crankcase, a magnet core 121, provided with a coil 123, is attached to the pole shoes 119 by means

of screws 122. 124 indicates a cap, preferably of "plastic" material, serving as a cover and formed with an opening 125 for the passage of the ignition cable.

5 The arrangement and design of the commutator need not be described. It is located under the case 22 and is actuated by a crankshaft, through a drag crank. The mounting and design of the necessary condenser are also immaterial.

10 Having now particularly described and ascertained the nature of my said invention, and in what manner the same is to be performed, I declare that what I claim is:

15 1. In an auxiliary engine of the type described, a flywheel, a permanent magnet mounted on said flywheel, a casing surrounding said flywheel, spaced soft iron inserts imbedded in and extending through a wall of said casing adjacent said flywheel, an induction coil having a core mounted externally of said casing, and means for maintaining the respective ends of said core in contact with said soft iron inserts.

20 2. The device defined in claim 1, said soft iron inserts being cast integrally with said casing wall.

25 3. The device defined in claim 1, said casing wall being formed with a slot between said soft iron inserts, and insulating material filling said slot in a gas-tight manner.

HUGO RUPPE.
